FID FOR SPLICING ROPE

Venancio Adrias, II, Washington, D. C.

Application June 17, 1944, Serial No. 540,855

2 Claims. (Cl. 57—23)

1

This invention comprises a fid and method of making the same, the present application being a continuation in part of my previous application filed March 26, 1942, Serial No. 436,349, now Patent No. 2,394,884, issued February 12, 1946.

Although the fid of my previous application efficiently and effectively splices rope strands in accordance with the teaching of the invention, I have found that equally effective results may be obtained by a fid using considerably less material yet retaining the same shape and other desirable characteristics of my presently used fid.

An object of this invention is to provide a fid the body of which is constructed from a blank of material of predetermined shape, the blank being rolled to the desired configuration to provide a hollow body, a part of which is adapted for the reception of the strand being spliced.

It is a further object of this invention to provide a method of making a fid the steps of which include stamping or otherwise forming a blank of predetermined shape which is rolled to bring the marginal edges at one end of the blank, into close proximity, to form the entering end of the body, the opposite end of the blank forming a channel in which the strand to be spliced is clamped.

It is also an object of this invention to extend the side walls of the open end of the fid to provide stops in order to limit the extent of movement of the clamping member into the fid body, the fulcrum end of the clamping member being extended to increase the bearing area of the member to eliminate lateral movement.

Instead of making the fid body from a blank of material, it is also within the contemplation of this invention to mold or otherwise form said fid body from a plastic or other material.

Other objects of the invention will be apparent from the following description of the present preferred form of the invention, taken in connection with the accompanying drawings, wherein:

Figure 1 is a perspective view of a fid constructed in accordance with the present invention, showing the clamping member in open position;

Figure 2 is a longitudinal sectional view of the fid with a strand of rope mounted therein and showing the clamping member in closed position;

Figure 3 is a vertical sectional view taken on line 3—3 of Figure 2, looking in the direction of the arrows;

Figure 4 is a bottom plan view of the clamping member per se;

2

Figure 5 is a plan view of the blank from which the fid body is constructed;

Figure 6 is a detail fragmentary sectional view of a modified form of the invention;

5 Figure 7 is a sectional view taken on the line 7—7 of Figure 6, looking in the direction of the arrows; and

Figure 8 is a side elevational view of modified form of lid.

10 The fid body of the present invention consists of a blank generally designated 6. One end 7 of the blank is tapered to a point 8, the tapered end of the body being substantially triangular in plan. The inner end of the triangle issues, intermediate its lateral extremities, into a substantially oblong or rectangular body 9. The blank is uniplanar and each of the parts 7 and 9 is of approximately the same length. The rectangle 9 is provided with a pair of openings 10 formed adjacent the base of the triangle 7, as illustrated to advantage in Figure 5.

15 In forming the fid body the edges of the triangular end 7 of the blank are brought into contiguity as shown in Figure 1 to provide a tubular conically shaped entering end 11. During the same step, the edges of the rectangular end 9 are bent to bring the same into substantially parallel relation, also as illustrated to advantage in Figure 1. This provides a strand receiving 20 channel 12. The free margins of the channel are bent inwardly and downwardly to snugly embrace a major portion of the rope strand perimeter. A further step in forming the fid body is to depress the inner terminal of the conical entering end 11 to provide a finger depression 13 through the medium of which movement of the fid through a rope is facilitated.

25 As illustrated to advantage in Figure 2, the base of the fid body is curved or arched from approximately the point 14. The curve toward the entering end 11 is more pronounced than toward the aft or butt end of the body. I have found that this contour facilitates threading operation. In addition, this bowing of the body tends to a 30 better purchase of the strand. In other words, this construction provides an abrupt lip 15 which bites into the strand, as illustrated in Figure 2.

35 For the purpose of securing the strand in the channel 12, I provide a clamping element 16 consisting of a lid-like member, one end of which is coiled or convoluted, as indicated at 17 on a pin or shaft 18, the terminals of the pin being mounted in the openings 10. The free inner end of the lid 16 is extended to provide a tab 19 which 40 serves as an abutment engageable with the bot-

tom of the channel 12 to limit the movement of the lid into the channel. Since however the lid is constructed of a flexible material, the free end thereof may be flexed inwardly against the strand being threaded, as illustrated in Figure 2, to obtain a better purchase on the strand, if this should be necessary, especially where smaller diameter strands are employed. The ends of the sleeve, formed by the convolution 17 may be extended, as indicated at 17' beyond the sides of the clamping element or lid 16 to prevent lateral movement of the element and to provide a more substantial bearing surface. This is not necessary with plastic or wood bodies. Also the surface of the clamping element or lid may be roughened, as indicated at 22, to prevent slippage of the rope strand.

In the modification of the invention illustrated in Figures 6 and 7 of the drawings, lugs 19' are provided which extend inwardly from the sides of the channel and overhang the latter. With this form of invention, the tab 19 is omitted from the lid 16 since the lugs will limit the inward movement of the lid into the channel.

In use, the strand of rope as indicated at 20, is mounted in the channel 12 following which the clamping element 16 is urged into engagement therewith. When the strand is forced downwardly under pressure of the element 16, displacement is prevented, not only because of the conformation of the channel and the pressure element, but likewise because of the vise-like grip on the strand, due to the upwardly canted lip 15. As set out above, movement of the clamping element into the channel 12 is limited by reason of the tab 19 in the form of invention shown in Figures 1 to 3 inclusive and the lugs or stops 19' in the form of invention shown in Figures 6 and 7. This prevents distortion of the channel and undue strain on the axis of the clamping element. At the same time, ample pressure is permitted to positively clamp the strand. The lugs 19' are depressed or countersunk in the channel 12 and when the clamping element is in a closed or operative position, the upper face of the element is in substantially the same plane with the top of the channel sides.

I have found that a fid constructed in accordance with the teaching of the present invention provides a lightweight relatively inexpensive device which will produce substantially the same results as the fid of my previous application, referred to supra. Furthermore, it is to be noted that for certain kinds of work, it is possible to eliminate the clamping element 16, with a corresponding elimination of the shaft 18, tab 19 and lugs 19', especially with lighter weight material, where extreme pressure in forcing the fid

through the body being spliced is unnecessary. The strand may be laid in the channel and pressure brought to bear thereon with the thumb or finger, especially in the zone overhanging the lip 15.

When the fid body is molded from a plastic or like material, the pointed end thereof may be made hollow, as illustrated in Figure 2. With the molded plastic body I prefer to employ a modified form of lid wherein the fulcrum end thereof is enlarged as indicated at 21. The base of the enlarged end is formed in the shape of an arc, permitting free opening movement of the lid, yet limiting the extent of inward movement into the fid body against the rope strand 20, except such as is permitted by the inherent resiliency of the lid.

Various other changes may be made in the invention within the scope of the claims hereto appended.

What I claim is:

1. A fid comprising an integral tubular body one end of which is closed and tapered to a point, the opposite end being of channel shape for the reception of a rope strand to be spliced, a clamping element pivotally mounted in said channel in close proximity to the inner terminal of the closed end of the body, the terminals of the engaged end of said element being extended beyond the sides of the latter, lugs formed on the margins of the channel in proximity to the axis of the clamping element, the lugs being in the path of movement of said element to limit the extent of movement of the latter into the channel.

2. A fid comprising a hollow integral body, tapering to a point at one end, the opposite end of the body being open to receive a strand of rope to be spliced, a clamping member one end of which is pivotally mounted in the body, the opposite end of said member overhanging the open end of the body and adapted to be urged against the strand during the splicing operation and lugs extending from the side walls of the open end of the body to limit movement of the clamping member into the body.
